UNITED STATES PATENT OFFICE.

AUGUST GIACOPINI, OF TORRINGTON, CONNECTICUT.

WHIPPING HOCKEY TOP.

Application filed September 15, 1922. Serial No. 588,330.

To all whom it may concern:

Be it known that I, AUGUST GIACOPINI, a citizen of the United States, and a resident of Torrington, county of Litchfield, and 5 State of Connecticut, have invented certain new and useful Improvements in Whipping Hockey Tops, of which the following is a specification.

This invention relates to toy spinning-tops, and more particularly to a toy spinning-top which is adapted to be kept in motion by the use of a whip.

One object of this invention is to provide a whipping top of the above nature which 15 will be very stable in its operation, and which may be easily kept spinning without requiring a high degree of skill.

A further object is to provide a whipping top of the above nature which will be 20 simple, cheap to manufacture, and very efficient and durable in use.

With these and other objects in view, there 25 has been illustrated on the accompanying drawing one form in which the invention may be conveniently embodied in practice.

Fig. 1 represents a perspective view of the 30 whipping top and the whip, showing the manner in which they are held by the hand of the user, preparatory to starting the top spinning.

Fig. 2 is a side view of the top.

Fig. 3 is a side sectional view of the same.

Fig. 4 is a view of the top taken from above.

Fig. 5 is a view, with parts broken away, 35 of the whip handle and cord employed for spinning the top.

Former whipping tops have always proven 40 unsatisfactory in use, generally due to the difficulty of manipulating them. Such tops were usually top-heavy and unbalanced, and it was necessary to strike them with the whip cord at certain specified areas or positions in the height of the tops. An inexperienced person using such a top was quite apt 45 to strike at the wrong place, with the result that the top would soon run down on account of insufficient rotative momentum, or would become unbalanced and fall over.

Moreover, when a blow was struck on such 50 a top at a point above or below the specified area, the cord would not wrap itself about, but would slide off without giving the top any increment of spinning motion. In most 55 cases, such a blow would upset the top, and as the device was top-heavy, it would be

unable to right itself, and would soon stop spinning entirely.

With the present invention, the above and other disadvantages have been largely, if 60 not entirely avoided. This has been accomplished by providing a top of improved shape, having its body so proportioned that the whipping cord will frictionally engage the surface thereof, no matter what portion 65 is struck. The center of gravity of the top has also been lowered by cutting away the upper outer edges of the top so that it will be able to right itself quickly in case it is accidentally upset.

Referring now to the drawings in which like reference numerals denote corresponding parts throughout the several views, the 70 numeral 10 designates the top proper, which may be made of any suitable material, but 75 which is preferably constructed of hard-wood. The upper or dome portion 11 of the top body comprises a section of a sphere, as clearly shown in Figs. 2 and 3, and the intermediate portion 12 of the top is oval-shaped, having its diameter diminished 80 from the upper to the bottom portion thereof. The bottom of the intermediate section 12 is cut off at 13 at right angles to the axis 85 of the top, and has an inwardly and upwardly extending recess 14 provided therein to receive a metal peg 15. The peg 15 has a conical point 16 and a rounded head 17, the outer portion of the head 17 being 90 adapted to rest on the ground or floor during spinning, the base of said head lying in contact with the flat portion 13 of the intermediate section 12.

The spherical upper section 11 of the 95 whipping top is provided with a series of grooves 18 (three in this instance). These grooves 18 which are located adjacent the junction with the intermediate section 12, extend horizontally around the circumference of the top. The intermediate section 100 12 is also provided with a series of grooves 19, spaced somewhat further apart than the grooves 18, and located at a point about one fourth the distance from the bottom to the upper part of the top. The grooves 18 105 and 19 not only serve to enhance the ornamental appearance of the top, but also serve as friction areas, to enable a firm grip to be obtained by a whip cord 20 which is carried by the whip handle 21. The whip cord 20 passes through an opening 22 in the end 110 of the handle 21, and has a knot 23, adapted

to prevent the end of the cord being pulled through the opening 22. The cord which is circular in cross section is preferably constructed of leather, but if desired, other materials such as hemp twine, braided cotton fabric, or the like, may be employed.

In operation, the top is first started spinning by placing it between both hands and moving one hand rapidly over the other. 10 This will give the top sufficient angular momentum to sustain it in spinning position for a short period.

An alternative method of starting the top spinning which requires the use of only one hand is shown in Fig. 1. According to this method, the whip cord 20 is wrapped around the central portion of the top between the grooves 18 and 19, in the same manner in which the string is wound about the common spinning top preparatory to spinning. 20 The cord is held in position by means of the thumb and fore finger, and the top is started spinning by giving a sudden pull with the whip handle, whereby the cord will engage the surface of the top with sufficient friction to rotate it. After the top has been started spinning, it is thereafter kept in rotary motion by striking it a series of sharp sudden blows with the whip cord 20, the 25 handle of the whip being held in the hand of the operator.

One advantage of this invention is that a single top may be kept continuously spinning without rewinding for an indefinite 35 time—the time of spinning being entirely dependent upon the will of the user.

A further advantage of this top over previous devices is that it may be engaged by the cord at any point on its height, and 40 not necessarily at a particular area or section, as was the case with previous whipping tops. Moreover, the bottom of the top is not brought to a sharp point, but is rounded. The sides of the top are also curved in such 45 a manner that the bottom of the top will be relatively wide, permitting the whip cord to more readily engage and wrap itself around the body of the top instead of slipping down as would be the case on a top having straight 50 conical sides.

The present form of top will be found especially useful as a means for healthful recreation and exercise. Competition be-

tween individuals may be easily arranged to determine who can keep a single top spinning longest, or who can keep the largest number of different tops spinning at the same time.

Another attractive competition in which the present invention may be employed is 60 a hockey game. In such a competition, the top will be used in place of the usual ball or puck, and each player will be given a whip instead of an ordinary hockey stick. Otherwise the game will be played by the 65 customary rules.

While there has been disclosed in this specification one form in which the invention may be embodied, it is to be understood that this form is shown for the purpose of 70 illustration only, and that the invention is not to be limited to the specific disclosure, but may be modified and embodied in various other forms without departing from its spirit. In short, the invention includes all 75 the modifications and embodiments coming within the scope of the following claim.

Having thus fully described the invention, what is claimed as new, and for which it is 80 desired to secure Letters Patent, is:

A whipping top comprising a substantially egg-shaped body portion larger at the top than at the bottom, said body portion having a smooth unobstructed spherical dome section at its upper end, a smooth intermediate convexly curved section, and a smooth curved unpointed peg section at its lower end, whereby the top will be permitted to rock over when struck by a whipping cord permitting said cord to slide under said top, said body portion having a series of cord engaging grooves between its dome and its intermediate section and a second series of cord engaging grooves between said curved peg section and said intermediate section, whereby, when the top is struck by said cord at any point between its dome section and its peg section, said cord will be prevented from slipping off and will frictionally engage in one of said series of cord 90 engaging grooves to impart a spinning motion to said top.

In testimony whereof, I have affixed my signature to this specification.

AUGUST GIACOPINI.
